DESIGN FOR AN ELECTRIC FAN

Walter A. Spear, Cincinnati, Ohio, assignor to
Victor Electric Products, Inc., Cincinnati, Ohio,
a corporation of Ohio

Application March 12, 1941, Serial No. 99,529

Term of patent 7 years

To all whom it may concern:

Be it known that I, Walter A. Spear, a citizen of the United States, residing at Cincinnati, in the county of Hamilton and State of Ohio, have invented a new, original, and ornamental Design for an Electric Fan, of which the following is a specification, reference being had to the accompanying drawing, forming a part thereof.

Figure 1 is a perspective view of an electric fan showing my new design.

Figure 2 is a bottom plan view looking up at the fan.

Figure 3 is a side elevational view of the fan.

I claim:

The ornamental design for an electric fan, as shown.

WALTER A. SPEAR.
